UNITED STATES PATENT OFFICE.

FRANK CUPELLI, OF POINT MARION, PENNSYLVANIA.

SAFETY-RAZOR.

941,231.

Specification of Letters Patent. Patented Nov. 23, 1909.

Application filed May 25, 1909. Serial No. 498,141.

To all whom it may concern:

Be it known that I, FRANK CUPELLI, a citizen of the United States, residing at Point Marion, in the county of Fayette and State of Pennsylvania, have invented new and useful Improvements in Safety-Razors, of which the following is a specification.

This invention relates to razors, and more particularly to those of the safety type, and 10 has for an object to provide a safety razor which will be constructed particularly on the lines of the well known form of razor, but which will be provided with a member hingedly connected to the usual form of 15 protecting receptacle, and which will be provided with a plurality of cutting blades arranged at the sides of the guard member having a series of projecting teeth or fingers which protrude slightly beyond the longitudinal cutting edges of the blades.

A still further object of my invention is to provide a razor whereby the blades may be conveniently removed at the will of the operator to permit the insertion of new blades 20 upon the removal of worn ones.

Other objects and advantages will be apparent as the nature of the invention is better set forth, and it will be understood that changes within the scope of the claim may 30 be resorted to without departing from the spirit of the invention.

In the drawing, forming a portion of this specification and in which like numerals of reference indicate similar parts in the several views:—Figure 1 is a side elevation of a portion of my improved razor. Fig. 2 is a detail perspective view of the guard member. Fig. 3 is a vertical section taken on the line 3—3 of Fig. 1. Fig. 4 is a detail perspective view of a portion of the razor.

Referring now more particularly to the drawing, there is shown a razor comprising a member 1 provided with a reduced portion 2 pivotally connected at 3 between the arms 4 of a receptacle or protecting casing 5 which may be of the usual form employed in razors having the customary pivoted blades. The member 1 is provided with a rectangular body portion 6 provided with inclined

end walls 7. The member 1 is provided with 50 a longitudinally extending bead or rib 8 which is reduced in diameter to that of the member 1 and forms at each side of the said bead or rib a longitudinally extending shoulder 9. A guard member 10 is provided 55 and has inclined end walls 11 arranged to frictionally engage the end walls 7 of the member 1 and has its lower edge seated upon the bead or rib 8.

Blades 12 are arranged at the sides of the 60 guard 10 and have their lower edges seated against the shoulders 9 and their end walls seated against the end walls 7 outwardly of the end walls of the said guard. The blades 12 are each provided with a beveled longitudinal edge 13 which are disposed slightly beneath or below the plane of the teeth 14 of the guard. The construction as herein shown is such that when the inclined or beveled walls 11 of the guard are properly 70 engaged with the correspondingly formed walls 7 the said guard will be held against movement in an outward direction. It will also be seen that when the walls 15 of the blades 12 are seated against the walls 7 they 75 will also be held against outward sliding movement. The member 1 is provided at suitably spaced points with pivotally mounted retaining members or yokes 16 having spaced spring arms 17 adapted to be engaged with the blades 12 upon their outer faces so as to prevent the said blades from becoming misplaced.

The razor as herein shown and described is extremely simple in construction and is 85 capable of being operated as in the mode of operation of the ordinary and well known form of razor. The construction permits of the removal of the guard 10 and the blades 12 so that the latter can be sharpened or replaced by new blades and the former sterilized or cleaned.

I claim:—

A razor comprising a receptacle having a member pivotally connected thereto provided with a cutaway portion arranged to form adjacent to the ends of the member inclined walls, a guard having inclined walls

for frictionally engaging the inclined walls of the member and arranged for engagement with the walls so as to hold the guard against sliding movement in an outward direction, blades at the sides of the guard provided with inclined end walls for engaging the inclined walls of the member, and blade retaining means carried by the member

adapted to engage the blades and to hold them against the sides of the said guard. 10

In testimony whereof I affix my signature in presence of two witnesses.

FRANK CUPELLI.
